STAPLER

Edward L. Sibley, Bennington, Vt.

Application June 29, 1937, Serial No. 151,045

16 Claims. (Cl. 1—48)

This invention relates to staplers, and it has particular reference to devices of this character in which, by appropriate movement of the stapler parts, staple-forming wire is fed from a supply 5 of same to the operative mechanism of a stapler head which severs from the supplied wire a length thereof adequate for the formation of the staple, forms the staple from such length of wire, causes the formed staple to be driven through the 10 papers or the like to be stapled together, and appropriately clinches the staple, all in a single stapling operation, the return movement of the parts to normal position being instrumental to permit feeding to the stapler head from the supply 15 of wire another length of wire adequate for the formation of another staple upon repetition of the stapling operation.

One object of the invention is to provide a stapler having, in general, the characteristics 20 hereinabove recited in which the operative parts are of rugged, durable construction, compactly assembled, and capable of functioning repeatedly in an efficient and satisfactory manner.

Another object of the invention is to provide a 25 device of the character referred to of relatively few parts, which parts are so arranged and assembled as to make them capable of easy access for adjustment, repair and replacement, if necessary.

30 In the embodiment illustrated in the drawings, and hereinafter particularly described, the device of the invention takes the form of a plier-type hand tool wherein the movements of the operative parts are accomplished by actuation of the 35 operating handles or handle levers upon their pivotal connections, and the compactness of the arrangement of the parts of the device, particularly as regards the supply of staple-forming wire, which generally is in reeled form enclosed with- 40 in a magazine or casing, is enhanced by location of such supply between the plier handles in what would normally be waste space.

It will be understood that, although as just 45 described, and as will hereinafter become more apparent, the invention, in the form shown, is embodied in a plier-type hand implement, its essential novel characteristics are capable of embodiment in other well known types of implements of this character, such, for example, as the 50 so-called desk type which includes a supporting base.

The invention contemplates a stapler including 55 a stapling head, means for supplying staple forming wire to said stapling head, whereby it may be formed into staples and these staples

driven, an anvil against which the staples may be clinched, and means for imparting an appropriate succession of movements to the parts of said stapling head, wire-supplying means and anvil, whereby wire may be fed in measured quantities to the stapling head, formed into staples, and the thus formed staples driven and caused to penetrate papers or other materials to be stapled, and clinched to secure such papers or other materials, all as will be explained herein- 10 after more fully and finally claimed.

In the accompanying drawings illustrating the invention, in the several figures of which like parts are similarly designated,

Figure 1 is a side elevation of the invention 15 embodied, as hereinbefore mentioned, in a hand implement of plier type.

Fig. 2 is a side elevation of the opposite side of the device illustrated in Fig. 1.

Fig. 3 is a fragmentary top plan view of the 20 device.

Fig. 4 is a fragmentary detail illustrating the wire clutch in engaged position, as distinguished from its disengaged position illustrated in Fig. 2.

Fig. 5 is an enlarged, fragmentary, longitudi- 25 nal, sectional elevation of the stapler head and anvil.

Fig. 6 is a fragmentary front elevation of the 30 stapler head and anvil, looking in the direction of the arrow, Fig. 5.

Fig. 7 is a fragmentary sectional elevation illustrating a detail of certain wire feeding elements.

Fig. 8 is a view similar to Fig. 5 but showing the 35 parts of the stapler head in the positions assumed thereby after formation of the staple from an appropriate length of supplied wire, and

Fig. 9 is a view similar to Fig. 8, but illustrating the parts of the stapler head in the positions assumed at the completion of the staple clinching 40 operation.

Fig. 10 is a bottom view of the wire magazine and associated parts.

In the embodiment of the invention illustrated, the stapler includes a stapler head A, an anvil B and a wire supply C operatively assembled in 45 plier-type actuating means.

These actuating means include a handle member 1 of bifurcated form providing arms 2 and 2' pivoted upon a bolt or other suitable pivot means 3 at the opposite sides of a head frame 4, 50 and carrying in fixed relation between their extremities 5, 5' the anvil block 6. The head frame 4 is provided with depending ears 7, 7', or the like, to which are pivotally connected at 8 and 8' the extensions 9 and 9' of a bifurcated handle 55

member 10 complementary to the handle member 1. By this arrangement of parts, it will be seen that as the handle members 1 and 10 are grasped and pressed together, the extensions 2, pivoting about the pivot 3 will first function to move the anvil block 6 into contact with the under surface of the head frame member 4, or into contact with papers or the like to be stapled, and then the handle 1 and head frame member 4 will, upon continued closing pressure on the handles, function as a unit pivoted upon the pivots 8, 8', so that relative movement will be imparted about these pivots 8 and 8' to the head frame member 4 and the extensions 9, 9' of the handle 10.

The head frame member 4 is preferably of channel formation, as indicated particularly by the showing of Figs. 3 and 6, and carries the parts whereby the operations of forming, driving and clinching a wire staple, from appropriately supplied wire, may be accomplished. These parts include a yoke 11 provided at its opposite sides with slides 12 cooperating with and adapted for sliding movement in guides 13 provided in the inner faces of the sides of the head frame member 4 and flanking an opening 13' in the bottom thereof in alignment with the yoke. Sliding movement is imparted to the yoke 11 by means of trunnions 14, 14' which engage cam slots 15 and 15' in the extensions 9 and 9' of the handle lever 10, so that when the handles are closed together, as hereinbefore indicated, the trunnions 14, 14', following the contour of the cam slots 15, 15' will be moved downwardly to the limit of their downward movement as determined by the conformation of the cam slots 15, 15' and by slots 16, 16' in the sides of the frame 4. The yoke 11 is recessed as indicated at 17 so that when depressed it will span a mandrel 18 mounted for sliding movement longitudinally of the head frame 4 between the sides thereof. Movement of this mandrel in one direction (to the right, Figs. 5, 8 and 9) is imparted to it by means of cam members 19 carried by the yoke 11 which engage a cam follower member or block 20 carried by the mandrel 18, and movement of the mandrel in the reverse, or return, direction is imparted by a spring 21 attached to it and to the head frame 4 as indicated at 22.

In operative alignment with the recess 17 of the yoke, and slidably in the yoke in suitable bearings, is a staple driver 23 having at its upper end a combined head or stop and cam contact member 24 which latter, during an appropriate portion of the closing movement of the handles 1 and 10 will be engaged by a cam surface 25 formed upon a cam block secured between the extensions 9, 9' of the handle 10.

The wire 26 from which the staples are formed is fed to the head transversely thereof and just above the upper surface of the mandrel 18 through a feed block 27 to which is connected a feed tube 28 which leads from a clutch abutment member 29 over which the wire 26 runs and upon which it is subjected to the action of an automatically operating pivoted clutch member 30 having an extension 31 normally engaging the rear edge 32 of the extension 9'. This clutch member 30 receives its pivotal movement in response to cooperation between the parts 31 and 32, and to the pressure exerted by a spring 33 bearing against it. The abutment member 29, clutch member 30 and spring 33 are all carried by a bracket 34 fixed to the head frame member 4, and this bracket also carries an extension 35 of the feed tube 28, which extension provides a

guide for feeding the wire from the supply C thereof to the clutch abutment member 29.

This wire supply preferably includes a casing or magazine 36 appropriately separably connected to its cover 37, which latter is rotatably secured to an extension 38 of the head frame member 4, and within this casing or reservoir is mounted a wire reel 39 rotatable upon a pin 40 extending through its hub or core and having bearings in the casing 36 and its cover 37. The wire 26 emerges from the casing through an opening 41 and leads therefrom over a friction block 42 and thence into and through the tube 35, clutch means 29-30, tube 28 and feed block 27 to the stapler head.

Various means may be employed for imparting intermittent rotative movement to the casing 36 to measure off from the reel lengths of wire adequate to form staples upon subsequent projection or feed into the stapler head. As one such means, there is shown depending from the under side of the casing 36, an eccentrically arranged pin 43 transversely bored to receive a sliding link 44 carrying a stop 45 and having its end connected at 46 with the handle lever 10. By this arrangement, it will be seen that as closing movement is imparted to the handles the clutch member 30 will be released, and under the influence of its spring 33 will assume the position illustrated in Fig. 4, wherein its wire engaging end will bear firmly against the wire and hold it in immovable contact with the abutment member 29. Simultaneously, the stop 45 will have been engaged with the pin 43 and, as the closing movement of handle levers is continued, will cause a partial rotation of the casing 36. Inasmuch as the wire 26 is held against movement by means of the clutch 29-30, this partial rotation of the casing 36 (clockwise Fig. 3) will cause an appropriate length of wire to be unwound from the reel 39, any excessive unwinding being prevented by means of a spring or other brake member, such as that shown at 47, or its equivalent, which bears against the reel 39. It will be noted that, as the wire is thus unwound from the reel, the friction block 42, and a resilient friction finger 50 bearing against the wire and holding it in contact with the friction block, will slide over the wire and recede from the end of the tube 35, and hence the length of wire between the parts 42-50 and the clutch means 29-30 is increased by an amount sufficient to form a staple. Upon subsequent release of the handles 1 and 10, the casing 36 will be returned to normal position by reverse rotation imparted to it by a spring 51, and the frictional engagement on the wire, imparted by block 42 and finger 50, will cause the length of wire previously measured off by unreeling to be fed forward to the stapler head, the clutch 29-30 having, meanwhile, been released by cooperation of the parts 31-32.

It has been found that a length of wire amounting to approximately $1\frac{1}{2}$ ' is adequate for the formation of an appropriate staple, and the device is preferably so designed and adjusted that upon each closing and opening movement of the handles this amount of wire will be fed from the reel of the magazine to the stapler head. Obviously, the amount of rotation imparted to the casing 36 may be adjusted by appropriate adjustment of the stop 45, or by appropriate adjustment of the pin 43, which latter may be adjustably secured in either an arcuate or a radial slot 43', Fig. 10, in the bottom of the casing 36.

Moreover, in order that when the casing 36 is 75

rotated by closing movement of the handles, under the influence of the link 44 and stop 45, it may not prematurely return under the influence of the spring 51 upon its return or wire feeding stroke, there is provided a latch member operating in timed relation to the actuation of the staple forming parts of the stapler head. This latch member preferably includes a spring-pressed pin 57 adapted for engagement with a tooth 58, or the like, (see particularly Fig. 3) on the casing 36 or its cover 37, and this pin is carried in a bearing member 59 mounted on a slide 60 guided in a slot 61 in the bottom of the frame 4 and attached to the sliding mandrel 18.

In the device as designed and constructed, the handle lever 10 is so formed that the pin 43, and preferably also the edge of the casing 36 will strike upon the appropriately formed surfaces 52 and 53, respectively, of the handle lever. Opening movement of the handle levers under the influence of the spring 54 is limited by a stop shoulder 55 which cooperates with the under surface of the anvil block 6 and by a stop pin 56 arranged in the head frame member 4 and against which the part 2' of the handle 1 abuts, as will be referred to hereinafter.

To facilitate threading of the wire through the tube 28 and into the feed block 27, the feed block (see Fig. 7) has a conical bore 27' terminating in the exit or feed aperture or orifice for the wire, and the tube 28 is depressed at 28' to form a guide the tendency of which is to project the end of the wire into the conical bore of the block 27. It will be noted, further, that there are no off-standing projections against which the end of the wire might abut when being threaded through the tube 28 and into the feed block 27, and that, therefore, the threading may be expeditiously accomplished.

The operation of the device is substantially as follows: Assuming that an appropriate reel of wire has been arranged within the reservoir or casing 36, and the parts thereof suitably assembled, and the wire 26 threaded through its various feed devices and into the stapler head over the mandrel 18 so that its end substantially abuts against the remote wall of the head frame member 4, as illustrated in Fig. 6, papers or the like to be stapled together will be inserted in the space between the anvil block 6 and the lower face of the head frame member 4. Then, when the handles 1 and 10 are grasped, and pressure applied to close them together, the first portion of this closing movement will, as hereinbefore stated, be a movement of the handle lever 1 about its pivot 3 which will result in closing the anvil block 6 beneath the opening 13' and against the lower face of the bottom of the frame member 4 to hold the papers between these parts, and to suitably locate the anvil block for the subsequently occurring staple driving and clinching operation. Continued closing movement of the handles 1 and 10 will cause a pivotal action around the pivots 8, 8' and will result in the depression of the yoke 11 by cooperation of its trunnions 14, 14' with the cam slots 15, 15', until the yoke has reached the limit of its downward movement, as illustrated in Fig. 8. The operation of the staple-forming parts thus far described has resulted in severing the length of wire which projects into the stapler head and in bending it around the mandrel 18 to staple form, as illustrated in Fig. 8, the staple being retained in the grooves 11' and 23' (see particularly Figs. 6 and 8) in the yoke 11 and staple driver 23, respectively. Meanwhile,

the mandrel 18 will have been gradually retracted, during the staple-forming operation, under the influence of the cam members 19 cooperating with the follower block 20, until the mandrel is completely withdrawn from between the arms of the yoke 11, and out of position to interfere with subsequent depression or staple driving operation of the staple driver 23. After the mandrel has been thus withdrawn, the staple driver 23 may, of its own weight descend, carrying with it the formed staple, until the ends of the legs of the staple pass through the opening 13' and contact with the sheets of paper or the like to be stapled together, or it may have retained its original elevated position, as indicated in Fig. 8, with the formed staple similarly elevated and thus retained by frictional engagement of its legs with the grooves 11' of the yoke. However, now, upon completion of the closing movement of the handles 1 and 10, the cam surface 25 bearing against the cam contact member 24 of the staple driver 23 will, by its rotative sliding engagement therewith, cause the staple driver 23 to descend, carrying with it the formed staple and causing the ends of the staple to be driven through the sheets of paper or other material and clinched in the clinching recess 6' of the anvil block 6. During this completion of the stapling operation the trunnions 14, 14' will be accommodated in the offset portions of the cam slots 15, 15' (see Fig. 9).

During these staple forming and clinching operations, it will be apparent that, as the edge 32 of the member 9' moves away from the part 31 of the clutch member 30, the clutch member, 35 will, under the influence of its spring 33, turn upon its pivot, as indicated in Fig. 4, to immovably grip that portion of the wire 26 which is exposed upon the abutment member 29, and that while the wire is thus held against movement, the casing 36 will be rotated, by cooperation of the parts 43-45, all as previously described, and a length of wire suitable for the formation of a subsequent staple, will be unreeled from the supply on the reel 39. Meanwhile, also, the latch pin 57 will have engaged the tooth 58, and reverse rotation of the casing 36 under the influence of spring 51 will thereby have been prevented.

Now, upon release of pressure upon the handles 1 and 10, permitting them to separate under the influence of the spring 54, they will return to normal position, the anvil block 6 will move away from the frame member 4 and the stapled papers or the like will be released. Also, the yoke 11 will be returned to the position illustrated in Fig. 5, carrying with it the staple driver 23, and the mandrel 18 will be returned to its normal position beneath the yoke 11 and staple driver 23. Moreover, return of the mandrel 18 to normal position will release the latch pin 57 from the tooth 58 of the wire reservoir and the wire reservoir, under the influence of the spring 51 will rotate (counter-clockwise, Fig. 3) and, due to the grip of the parts 42 and 59 upon the wire, will feed the measured length of wire into the stapler head above the mandrel 18 as indicated in Fig. 6, so that the device is ready for another stapling operation; it being understood that when the edge 32 of the member 9' strikes the extension 31 of the clutch 30, the clutch 30 will be released, thus permitting the wire to be fed as desired.

Although the stop shoulder 55 may be depended upon for limiting the return movement of the lever 10 to normal position, the fact that the lever 1 has an independent movement about its

pivot 3 under the influence of spring 54, makes it necessary to limit such movement by means of the stop pin 56 or equivalent means, and thereby the return of all of the staple-forming parts to operative position may be definitely ensured, as any excess movement of lever 10 will cause its cam slots 15, 15' to disturb the required adjustment of the yoke 11 and its associated parts.

Various changes and modifications are considered to be within the spirit of the invention and the scope of the following claims.

What I claim is:

1. In a stapler adapted to form staples from wire and to drive them, a stapler head, an anvil, and means for supplying staple-forming wire to said head, two pivoted members for actuating said head, anvil and wire-supplying means during the staple forming and driving operations, said head having a frame to which said actuating members are pivoted and confining staple forming and driving means including a yoke and a staple driver relatively movable, and separate camming means carried by one of said actuating members and cooperating directly with said yoke 25 and staple driver respectively to impart desired staple forming and driving movement thereto.

2. In a stapler adapted to form staples from wire and to drive them, a stapler head, an anvil, and means for supplying staple-forming wire to said head, two pivoted members for actuating said head, anvil and wire-supplying means during the staple forming and driving operations, said head having a frame to which said actuating members are pivoted and confining staple forming and driving means including a yoke and a staple driver relatively movable, said yoke provided with laterally offstanding trunnion means, and one of said actuating members provided with camming means directly engaging said trunnion 40 means and with camming means directly engaging said staple driver, whereby relative movement of said actuating members will impart relative staple forming and driving movement to said yoke and staple driver.

3. In a stapler adapted to form staples from wire and to drive them, a stapler head, an anvil, and means for supplying staple-forming wire to said head, pivoted means for actuating said head, anvil and wire-supplying means during the staple forming and driving operations, said head including a frame to which said actuating means are pivoted and carrying staple forming and clinching means comprising as relatively movable parts a yoke, a mandrel and a staple driver, said yoke serving to sever said wire, and said yoke and mandrel serving jointly during relative movement to shape said wire to staple form and said staple driver serving to clinch said staple against said anvil, and camming means carried by 60 said actuating means and movable with respect to said head and cooperating directly with said yoke and staple driver, respectively, to impart operative movement thereto.

4. In a stapler adapted to form staples from wire and to drive them, a stapler head, an anvil, and means for supplying staple-forming wire to said head, pivoted means for actuating said head, anvil and wire-supplying means during the staple forming and driving operations, said head including a frame carrying staple forming and clinching means comprising as relatively movable parts a yoke, a mandrel and a staple driver, said yoke provided with means for imparting 70 movement to said mandrel and serving also to

sever said wire, and said yoke and mandrel serving jointly during relative movement to shape a staple from the severed portion of the wire, and said staple driver serving to drive and clinch said staple against said anvil, and camming means carried by said actuating means and movable with respect to said head and cooperating directly with said yoke and staple driver to impart operative movement thereto and through said yoke to said mandrel.

5. In a stapler adapted to form staples from wire and to drive them, a stapler head, an anvil, and means for supplying staple-forming wire to said head, pivoted means for actuating said head, anvil and wire-supplying means during the staple forming and driving operations, said head including a frame carrying staple forming and clinching means comprising as relatively movable parts a yoke, a mandrel and a staple driver, said yoke serving to sever said wire, and said yoke and mandrel serving during relative movement to shape said wire to staple form, and said staple driver serving to drive and clinch said staple against said anvil, and camming means carried by said actuating means and movable with respect to said head, and including cam members directly cooperating with said yoke and staple driver respectively, and functioning sequentially to impart operative movement thereto.

6. In a stapler, a stapler head, an anvil, and means for supplying staple-forming wire to said head, said head including a frame carrying relatively movable parts for forming a staple from such wire and for clinching said staple against said anvil and including a yoke and a staple driver, said frame pivotally connected with two operating members movable relatively to each other and to said frame, one of said members carrying said anvil and the other member provided with camming means cooperating directly with complementary parts of said yoke and staple driver, whereby relative pivotal movement of said operating members will actuate said staple forming and clinching means.

7. In a stapler, a stapler head, an anvil, and means for supplying staple-forming wire to said head, said head including a yoke a mandrel and a staple driver cooperatively associated for forming a staple and for clinching it against said anvil, lever mechanism for imparting staple forming and clinching movement to said yoke, mandrel and driver, said wire supplying means including a revoluble wire magazine carried by said head and actuated in response to movement of said lever mechanism, a wire guide extending from said magazine to said head, a connection between said lever mechanism and said magazine whereby actuation of said lever mechanism serves to rotate said magazine to measure off a predetermined length of wire and permit its subsequent feed to said head, and clutch mechanism interposed in said wire guide and operative in response to actuation of said lever mechanism to hold said wire against movement during said measuring off and for releasing the wire during said feed.

8. In a stapler, a stapler head including staple-forming parts, an anvil, and means for supplying staple-forming wire to said head, said wire supplying means including a tube through which the wire is appropriately conducted to said head and a member apertured to pass the wire to the staple forming parts of the head, said tube provided with an offset bend functioning to guide the wire to the aperture of said member and having in its wall adjacent to said bend an indenta-

tion serving to aid in threading the wire through said aperture.

9. A stapling implement of plier type, including a stapler head comprising a frame carrying staple forming and driving means, means for supplying staple-forming wire to said head, and a pair of operating handle levers having individual separated pivot means on said frame, one of said levers carrying a staple clinching anvil for cooperation with the staple driving means, and the other lever provided with means for actuating said staple forming and driving means.

10. A stapling implement of plier type, including a stapler head comprising a frame carrying staple forming and driving means, means for supplying staple-forming wire to said head, and a pair of operating handle levers having individual separated pivot means on said frame, one of said levers carrying an anvil normally spaced from 15 said frame but capable of movement by said lever into cooperative relation to said driving means and adjacent to said frame, whereby said frame and lever operate as a unit upon the pivot means of the other lever, said other lever provided with 20 means for actuating said staple forming and driving means.

11. A stapling implement of plier type, including a stapler head comprising a frame carrying staple forming and driving means, means for 25 supplying staple-forming wire to said head, and a pair of operating handle levers having pivot means on said frame, one of said levers carrying a staple clinching anvil for cooperation with the staple driving means, and the other lever provided with means for actuating said staple forming and driving means, said wire supplying means including a magazine mounted upon said frame and carrying staple-forming wire, and means 30 operatively connecting said magazine with one of said levers and responsive to relative movement of said levers to provide for relative movement between said magazine and the wire carried thereby to measure off staple-forming lengths of wire in response to staple forming and driving 35 actuation of said levers.

12. A stapling implement of plier type, including a stapler head comprising a frame carrying staple forming and driving means, means for supplying staple-forming wire to said head, and 40 a pair of operating handle levers having pivot means on said frame and movable relatively thereto and to each other, one of said levers carrying a staple clinching anvil for cooperation with the staple driving means, and the other lever provided with means for actuating said staple forming and driving means, said wire supplying means including a wire magazine carried by said frame and interposed between said levers, said levers 45 hence being movable relatively to said magazine.

during their closing movement toward each other, one of said levers formed for abutting engagement with said magazine to limit such closing movement.

13. A stapling implement of plier type, including a stapler head comprising a frame carrying staple forming and driving means, means for supplying staple-forming wire to said head, and a pair of operating handle levers having individual separated pivot means on said frame, one of said levers carrying a staple clinching anvil for cooperation with the staple driving means, and the other lever provided with means for actuating said staple forming and driving means, said levers capable of closing movement toward 15 each other to perform said staple forming, driving and clinching operations, resilient means for causing separating movement of said levers after completion of said operations, and means carried by said frame and cooperating with said 20 first mentioned lever and means carried by the other lever and cooperating with said anvil for limiting such separating movement.

14. In a stapler, a stapler head, and means for supplying staple-forming wire to said head including oscillatable wire-carrying means, said head including a movable mandrel and said wire-carrying means oscillated in timed relation to the movement of said mandrel, and cooperating means carried by said wire-carrying means and 30 by said mandrel, respectively, for arresting oscillation of said wire carrying means.

15. In a stapler, a stapler head, and means for feeding staple-forming wire to said head including an oscillatable wire magazine, said head provided with staple forming parts, means for imparting staple-forming movement to the parts of said head, means for imparting oscillatory movement to said magazine in timed relation to the movement of the parts of said head, and cooperative stop means carried by a staple forming part 40 of said head and by said magazine, respectively, for arresting oscillation of said magazine.

16. In a stapler, a stapler head, and means for feeding staple-forming wire to said head including an oscillatable wire magazine, said head provided with staple forming parts including a movable mandrel, means for imparting staple-forming movement to the parts of said head, means for imparting oscillatory wire-measuring-off 50 movement to said magazine in timed relation to the staple-forming movement of the parts of said head, means for imparting wire feeding return movement to said magazine, and cooperative stop means carried by said mandrel and by said magazine, respectively, for arresting return movement 55 of said magazine.

EDWARD L. SIBLEY.
